UNITED STATES PATENT OFFICE.

GEORGE McDOWELL, OF NEW YORK, N. Y.

INTERNAL-COMBUSTION ENGINE.

1,098,455.

Specification of Letters Patent.

Patented June 2, 1914.

Application filed August 17, 1912. Serial No. 715,567.

To all whom it may concern:

Be it known that I, GEORGE McDOWELL, a citizen of the United States, and resident of the city of New York, borough of Brooklyn, county of Kings, and State of New York, have invented certain new and useful Improvements in Internal-Combustion Engines, of which the following is a specification.

- 10 The object of my invention is to improve and simplify the valve mechanism and produce an efficient device positively operated at all times, without the use of springs and hence adapted to increase the efficiency of 15 the engine and render the operation of the valves practically noiseless. This I have accomplished by surrounding the upper end of the cylinder with two concentric valve rings each provided with slots or openings corresponding with the intake and exhaust ports 20 of the cylinder and adapted by rotative oscillation of the rings to open and close said ports periodically in accordance with the usual practice in four cycle type of combustion engines. My arrangement of the valve rings not only eliminates noise, but the annular sleeves present more surface so that the wear is less and the possibility of leakage at the valves is reduced to a minimum. 25 Furthermore my construction makes it possible to more completely surround the valve rings by water so that during operation they are kept cool thus avoiding any burning of the valve openings. 30 Preferably I have shown my invention in connection with a four cycle type of combustion engine although it will be understood that it may be used in other types of engines for which it is found adaptable. 35 In the accompanying drawings, Figure 1 represents a single cylinder engine in vertical section; Fig. 2 shows a section of the valve mechanism taken on the line 2—2 of Fig. 1; Fig. 3 shows the valve rings in elevation and 40 Fig. 4 shows a horizontal section thereof; Figs. 5 to 8 inclusive represent, diagrammatically, the relations between the valve members and the piston at the beginning of each of the four strokes; and Fig. 9 is a development of the valve ring movements for the 45 four stroke cycle.

In the drawings, 1 represents the crank shaft housing in which the crank shaft 2 is adapted to rotate.

3 represents the cylinder in which the 55 piston 4 is adapted to reciprocate. The piston is connected to the crank 5 by the connecting rod 6 in the usual manner. The engine cylinder is made double or is provided with a water jacket 7 in order to permit circulation of cold water about the cylinder and valve rings. The cylinder and water jacket are provided with enlarged annular extensions 3^a and 7^a above the end of the piston, which extensions are bored out to receive 60 two concentric valve rings 8 and 9. The cylinder head 10 is adapted to close the end of the extension and at its center projects downwardly at 10^a inside of the valve rings 8 and 9 to close the end of the cylinder, 65 thereby forming a compression chamber above the end of the piston. The cylinder head 10 is hollowed out or chambered at 11 for the circulation of water to keep the head and valve rings cool as desired. The head 70 is also provided with an opening 12 for the spark plug which may be inserted in any suitable or preferred manner. The downwardly extending central portion of the head 10^a is preferably also provided with 75 two radially extending openings or ports 13 and 14, one of which, 13, is the inlet port for the entrance of the gases to the compression chamber and the other, 14, is the exhaust port for the escape of the burned gases 80 after the explosion. These ports are adapted to register with corresponding openings through the annular extensions 3^a and 7^a which are connected in the usual manner with the supply and exhaust pipes. 85

The concentric valve rings 8 and 9 are mounted in the annular channel formed between the upper extension 3^a of the cylinder and the downwardly extending portion 10^a of the cylinder head and compression 90 chamber and are loosely mounted therein for movement or oscillation in a circumferential direction. Each valve member or ring 8 and 9 is provided with two or more openings located in such a position on the circumference of the respective rings that they may serve to open and close the ports 13 and 14 at the proper time during the four strokes as hereinafter more fully described. The openings 15 and 16 in the valve rings are 95 arranged to be brought into register with the inlet port 13 to open said inlet port for the admission of the explosive mixture, and

the openings 17 and 18 are adapted to be brought into register to open the exhaust port 14 at the desired time to permit the escape of the burned gases at the proper stroke after the explosion. It will be noticed that from the arrangement of the two sets of openings 15, 16 and 17, 18, that when the inlet port is fully open, the openings 17 and 18 will be out of register, and the exhaust port 14 will be closed. The valve rings 8 and 9 are reciprocated circumferentially to bring the openings 15 and 16 and the openings 17 and 18 into register therewith during the four strokes of movement of the piston in the manner to be hereinafter more fully described. The valve rings may be reciprocated in any suitable manner to obtain the desired results, but I have here shown the respective valve rings as provided with geared segments 19 and 20, the segment 19 being cast upon or secured to the inner ring 8 while the segment 20 is similarly secured to the outer ring 9. The outer ring 9 is provided with a slotted opening at 21 to enable the ring to be slipped into place over the inner ring, which slot is made T-shaped to provide for the reciprocation of the segment 19 connected to the inner ring. Meshing with the respective segments 19 and 20 are two gear segments 22, 23 which are pivotally mounted on the frame of the engine and adapted to be rocked or vibrated in any suitable manner to reciprocate the valve rings 8 and 9. In the present instance, these geared segments 22, 23 are mounted upon rock shafts 24 and 25, one of which, 24, is tubular and surrounds the other, as will be seen in Fig. 1 of the drawings. The two concentric shafts 24 and 25 are inclosed and supported by a shell or casing 26 which is secured to the engine frame or more properly, to the cylinder water jacket, and to an extension of the crank shaft housing. The lower ends of the shafts 24 and 25 are preferably provided with outwardly extending rock arms 27 and 28 secured to the respective shafts. Each of the rock arms 27, 28, is provided with a downwardly projecting pin or roller 27^a, 28^a, each of which is adapted to operate in a circular cam groove on the cam wheel 29. The cam groove 30 is adapted to operate on the pin 27^a projecting from the rock arm 27 and thereby oscillate the inner valve ring 8, while the cam groove 31 is adapted to operate on the pin 28^a in the rock arm 28 and oscillate the outer valve ring 9, as will be seen from the drawings. The cam wheel 29 is secured to a shaft 32 which is supported in suitable bearings 33 extending from the housing 1 as previously indicated. Preferably one end of the shaft 32 is provided with a spur gear 34 which is secured thereto and adapted to mesh with another spur gear 35 secured to the crank shaft 2, the relation between the

two gears 34 and 35 being such that it requires two complete revolutions of the crank shaft 2 for one of the cam shaft 32.

It will be understood that any suitable connection between the crank shaft and the cam shaft may be employed so long as the relation between the rotation of the crank shaft and the proper opening and closing of the inlet and exhaust ports during the four strokes is maintained.

By the form of device and the relation between the parts here shown, the operation of the valve rings by the crank shaft through the circular cams at the beginning of each of the four strokes is indicated in Figs. 5 to 8 inclusive, in which the relative position of the crank shaft, piston and valve rings is shown. In Fig. 9 is shown a development of the motions of the valve rings during the four stroke cycle. The openings 15 and 16 in the two valve rings 8 and 9 corresponding to the intake port, being indicated by the lower line of small rectangles, while the openings 17 and 18 in the valve rings 8 and 9 for the exhaust port are indicated by the upper line of small rectangles in this figure. The position of the inlet and exhaust ports 13 and 14 is indicated in Fig. 9 by the parallel lines extending horizontally across the lines of small rectangles representing the valve openings in the rings. Studying this figure in connection with Figs. 5 to 8, the various movements of the valve rings during the four strokes can be readily traced. Fig. 5 shows the piston at the top of its stroke with the intake valve just beginning to open, this point being indicated by the rectangles at the left end A of the lower line of development in Fig. 9. Following the development in Fig. 9 from left to right, it will be seen that the small rectangles, from step to step, are brought to overlap more and more in the field of or between the lines representing the intake port 13, and hence the intake valve continues to open wider as the piston moves down, and then the openings 15 and 16 move apart so as to close the intake port shortly after passing the line marked B, at which point the piston has reached the bottom of its stroke, and compression of the gases drawn into the cylinder will begin. This point is indicated in Fig. 6 of the drawings. During compression it will be seen that the intake valve openings in the rings move still farther out of line with the intake port 13 until the piston has returned to its uppermost position, completing the compression stroke, after which the explosion takes place, this point being indicated by the line C in Fig. 9, and represented by the position of the parts in Fig. 7. Continuing to trace the movement of the intake valve ring openings through the explosion and exhaust strokes indicated in Fig. 9, it will be seen

that the openings 15 and 16 are gradually brought back to the position in which the intake valve begins to open for a repetition of the four strokes, this position being indicated on the line E which corresponds with the position of the valve openings on line A at the left end of Fig. 9. Similarly tracing the movements of the valve openings with relation to the exhaust port 14, it will be seen from a study of the upper development in Fig. 9 that the exhaust port begins to open toward the end of the explosion stroke or just before the beginning of the up stroke of the piston on the exhaust stroke, the beginning of which is indicated in Fig. 8 of the drawings which represents the position of the parts when the valve openings are in a position also represented on the line D in Fig. 9. Further tracing the opening of the exhaust port from the line D to E in Fig. 9, it will be seen that the exhaust port is quickly brought to full opening and then gradually closed, complete closure of the exhaust port, however, not taking place until after the intake valves begin to open for the next stroke as will be seen by the position of the small rectangles on the line A at the left end of the upper line of the development in Fig. 9. It will thus be seen that during the operation of the engine, the exhaust port will be closed during the intake stroke, while the intake port is open and gases are being drawn into the cylinder. During the compression stroke or during the first up stroke of the piston as the gases are compressed, both intake and exhaust ports will be closed and will remain closed during the explosion stroke, toward the end of which the exhaust port will begin to open and will be fully opened during the up stroke of the piston when the burned gases will be forced out after which the four stroke cycle will be again repeated.

It will be understood that various modi-

fications in the specific form shown and described may be made without departing from the spirit of my invention.

I claim:

1. In an engine the combination of a reciprocating piston, a cylinder provided with inlet and exhaust ports both located on the same side of the cylinder, a pair of annular concentric valve members, concentric with said cylinder, provided with openings corresponding with said ports, a crank shaft adapted to be turned by said piston, a secondary shaft adapted to be driven by said crank shaft, and operative connections between said secondary shaft and said valve members for oscillating said members circumferentially and independently to alternately open and close said ports as said crank shaft is turned said connections being located on the opposite side of the cylinder from said inlet and exhaust ports. 65

2. In a reciprocating engine the combination of a cylinder provided with inlet and exhaust ports both located on the same side of the cylinder, a pair of annular concentric valve members concentric with said cylinder, each provided with openings corresponding with said ports and means located on the opposite sides of the cylinder from said ports for circumferentially oscillating each valve member independently to alternately open and close said ports, the arrangement being such that the corresponding openings in the valve members are brought into register with each other and with the respective ports to open the same and are moved out of 80 register to close said ports. 75

In witness whereof I have hereunto set my hand in the presence of two subscribing witnesses.

GEORGE McDOWELL.
